UNITED STATES PATENT OFFICE.

OSCAR E. MOUSA, OF FAIRBURY, ILLINOIS.

IMPLEMENT FOR PUSHING AND PULLING.

1,337,719.

Specification of Letters Patent. Patented Apr. 20, 1920.

Application filed June 4, 1919. Serial No. 301,634.

To all whom it may concern:

Be it known that I, OSCAR E. MOUSA, a citizen of the United States, residing at Fairbury, in the county of Livingston and 5 State of Illinois, have invented certain new and useful Improvements in Implements for Pushing and Pulling, of which the following is a specification, reference being had to the accompanying drawings.

10 This invention relates to certain improvements in implements for pushing and pulling, and has relation more particularly to an implement of this general character especially designed and adapted for use in the stretching of woven fence fabric or the like, and it is an object of the invention to provide a novel and improved implement of 15 this character which may be engaged with the work with convenience and operated 20 with facility.

It is also an object of the invention to provide a novel and improved device of this general character including an arcuate member provided at one extremity with engaging 25 means and having secured to its opposite extremity and at a point substantially central thereof with an operating member or lever.

The invention consists in the details of 30 construction and in the combination and arrangement of the several parts of my improved implement for pushing and pulling whereby certain important advantages are attained and the device rendered simpler, 35 less expensive and otherwise more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in elevation illustrating 45 an implement constructed in accordance with an embodiment of my invention and in applied position.

Fig. 2 is a view in perspective of the head as comprised in my improved implement.

50 Fig. 3 is a fragmentary view, partly in elevation and partly in section, illustrating a connection between the head and operating lever.

Fig. 4 is a fragmentary view, partly in 55 elevation and partly in section, illustrating the connection between the operating lever

and the inwardly directed arm comprised in the head, and

Fig. 5 is a fragmentary view in elevation of the clamping bars as herein embodied. 60

As disclosed in the accompanying drawings, H denotes a head consisting of an arcuate rigid member in excess of a semicircle and preferably substantially three-quarters of a circle. The head H is of a radius demanded by the requirements of practice and is provided at one extremity with a claw 1 for a purpose to be hereinafter more particularly referred to. The opposite end portion of the head H is provided with the inwardly directed and substantially radially disposed arm 2. 65

Overlying the arm 2 is an angular end portion or extension 3 of an elongated lever L and which lever L and the extension 3 thereof are preferably formed of metal. The outer end of the extension 3 is reduced to afford a stud 4 extending through an opening 5 formed in the head H at a point substantially in radial alignment with the 70 arm. The stud 4 is of such a length that after the same has been initially disposed through the opening 5, the outer portion of said stud can be upset, as indicated at 6, whereby the outer end of the angular portion 75 of extension 3 is effectively secured to the head H.

The arm 2 at a point substantially midway thereof is provided with a pair of transversely spaced openings 7 between which is 80 arranged the angular portion or extension 3 of the lever L. Straddling the portion or extension 3 of the lever L is a U-shaped member M and the side members or arms 8 of said member are disposed through the 85 openings 7. Engaged with the free end portions of the side members 8 are the clamping members 9 which engage the inner face of the arm 2, whereby the lever L, or more particularly the angular portion 90 of extension 3 thereof, is securely anchored to the arm 2. 100

The clamping members 9 preferably constitute nuts of a conventional type and by having said members 8 positioned inwardly 105 of the arm 2, the same are located in a manner whereby they offer no hindrance or interference with the use of the implement.

In practice, it is preferred that a pair 110 of clamping bars be engaged with the opposite sides of a fence fabric F or the like

and held thereto in a conventional manner by the clamping members B. The opposed faces of the bars B adjacent each end are provided with the registering notches 5 which, when the clamping bars B are in applied position, afford an opening through which the flexible member 11, preferably a chain, may be directed.

An end portion of the chain is suitably 10 anchored to a post or other support and the opposite end portion directed through an opening afforded by a pair of registering notches 10. The head H is then engaged with the outer edges of the bars B with the 15 claw 1 of said head H suitably engaged with a link of the chain. It is preferred that the claw 2 engage the chain 11 from below so that, upon forcing the lever L downwardly, the bars B will be moved in a direction to impose the requisite strain upon 20 the fabric F.

To hold the bars B against return movement under the influence of the fabric F, after said fabric has been pulled or stretched 25 by the implement, a removable pin 12 is inserted through a link of the chain in front of the bars B for contact with said bars B. By this means, the pin 12 may be arranged at any desired angle as necessitated by the 30 link of the chain through which it is directed. The operations of the implement may be thus repeated until the desired stretching of the fence fabric has been accomplished.

35 It will also be understood that after the work has been accomplished at one end portion of the bars B, the implement may be used in conjunction with the opposite end portion thereof. It is for this reason that it 40 has been found of advantage to provide the

lever L with the angular portion or extension 3, as by this means the implement can be used to advantage at a point on the bars B in close proximity to the ground level.

From the foregoing description, it is 45 thought to be obvious that an implement for pushing and pulling constructed in accordance with my invention is particularly well adapted for use by reason of the convenience and facility with which it may be assembled and operated, and it will also be obvious that my invention is susceptible of some change and modification without departing 50 from the principles and spirit thereof and for this reason I do not wish to be understood as limiting myself to the precise arrangement and formation of the several parts herein shown in carrying out my invention in practice except as hereinafter 55 claimed.

60 I claim:

An implement of the class described comprising a substantially arcuate head provided with engaging means at one end portion, the opposite end portion being provided with an inwardly directed radial arm terminating at substantially the axial center of the head, said head substantially in alignment with the arm being provided with an opening, a lever overlying the arm and having an end portion secured within the opening of the head, and means for securing the lever to the arm.

65 In testimony whereof I hereunto affix my signature in the presence of two witnesses.

70 OSCAR E. MOUSA.

Witnesses:

E. D. YODER,
E. F. SIMMONS.
